UNITED STATES PATENT OFFICE.

JULIEN PIETERS, OF PARIS, FRANCE.

APPARATUS FOR DISCHARGING VERTICAL RETORTS.

1,412,628.

Specification of Letters Patent. Patented Apr. 11, 1922.

Application filed July 1, 1920. Serial No. 393,292.

To all whom it may concern:

Be it known that I, JULIEN PIETERS, a subject of the King of Belgium, and a resident of 12 Rue de La Rochefoucauld, Paris, France, have invented new and useful Improvements in Apparatus for Discharging Vertical Retorts, of which the following is a specification.

The French Patent 484,492 dated February 16th, 1917, describes a method of discharging coke, in which the material after having been separated from the upper mass retained in the retort, is transported horizontally by a suitable known apparatus. This mechanism, however, does not convey the material beyond the vertical facing of the retort, and it is necessary to add a special apparatus for discharging the coke outside the retort.

The present invention relates to an apparatus for discharging the material at the base of vertical continuous distillation retorts, allowing the material to be conveyed directly outside the retort to the vehicles on which it is to be loaded.

As compared with known apparatus for discharging the material from the whole length of the retort, the present invention is characterized by the fact that the hydraulic seal which prevents leakage at the base of the retort, instead of extending to form a large reservoir closing in the whole of the bottom of the retort, and in which the material would therefore have to remain for a considerable time, consists simply of two small reservoirs arranged at the sides of the retort and into which the material to be discharged passes only for a few moments while being conveyed by an endless transporter device.

This arrangement affords the important advantage that the material can absorb only an extremely small proportion of water during its very short passage through the hydraulic seal.

The annexed sheet of drawings represents by way of example, one form of construction of the invention:

Figures 1-1^a is a section upon the centre-line of the retort at the base of the latter. Figure 2 is a transverse section on line 2-2 of Figure 1.

The retort A is sealed at its lower end by

two water-spaces a b of relatively small dimensions, into which there dip metal partitions a' b' so as to provide a hydraulic seal; 55 the reservoirs a and b are arranged on the centre-line of the retort and on either side thereof, outside the retort chamber.

The discharge of material is effected by an endless conveyor consisting of two side 60 chains c c connected together by slats c'; this conveyor extends over the whole length of the retort; as far as the driving and idler drums c² c³.

The material resulting from the distillation, for example coke, rests on the flooring d by means of the slatted chain, and can only come into contact with the water during the very short time necessary for passing through the water seal reservoir a located at 70 the side where the material is discharged.

The endless conveyor chains c c are guided in their travel beneath the retort as well as in their passage along the curves of the water-spaces a and b by sliding and protecting surfaces suitably arranged at c⁴ c⁵.

The endless transporting device c c' conveys the material directly to the wagons e, preferably after first making it pass over a riddle consisting of a fixed sieve e' in order 80 to remove the finer particles which fall into a hopper e² from which they are evacuated.

The conveyors of an entire battery of retorts may be operated by means of a single shaft c⁵ extending along the retorts on one 85 side and driving the several drums c² by any suitable transmission.

What I claim is:

1. An apparatus for the removal of material from the base of vertical continuous distillation retorts comprising an endless conveyor moving through the retort chamber, flooring underlying said conveyor and forming the bottom of said chamber, two water seals located at opposite ends of the retort 95 outside the chamber and through which the endless conveyor passes.

2. An apparatus for the removal of material from the base of vertical continuous distillation retorts comprising an endless conveyor moving through the retort chamber, flooring underlying said conveyor, and forming the bottom of said chamber, two water seals comprising two water basins located at 100

opposite ends of the retort outside the chamber, the endless conveyor passing therethrough, partitions fixed to the sides of the retort and dipping into the water basins, said basins consisting of depressions in the flooring; in combination with means guiding the conveyor in the curves of the flooring.

In testimony whereof I have signed my name to this specification.

JULIEN PIETERS.
